UNITED STATES PATENT OFFICE.

RUFUS JONES, OF PITTSBURG, PENNSYLVANIA.

NECK-YOKE.

SPECIFICATION forming part of Letters Patent No. 736,109, dated August 11, 1903.

Application filed April 14, 1903. Serial No. 152,493. (No model.)

To all whom it may concern:

Be it known that I, RUFUS JONES, a citizen of the United States of America, residing at Pittsburgh, in the county of Allegheny and State of Pennsylvania, have invented certain new and useful Improvements in Neck-Yokes, of which the following is a specification, reference being had therein to the accompanying drawings.

10 This invention relates to certain new and useful improvements in neck-yokes; and the object of the invention is primarily to provide a yoke by means of which the strain is so distributed as to cause no pinching upon 15 the neck of the animal, which is a serious objection to the neck-yokes of ordinary "pole" form.

A further object of my invention is to provide a neck-yoke which may be easily and 20 advantageously employed either on breast-strap double harness or with the form of harness embodying a collar and hames.

Briefly described, my invention comprises a yoke member which is preferably made of 25 several plies of leather stitched or otherwise secured together. This yoke member or piece is substantially triangular in form and is provided in its lower lobe with an opening to receive the end of the pole and in its upper two 30 lobes with openings through which are passed the neck-straps for attachment to the harness. Means is also provided whereby the neck member or piece is detachably connected to the pole of the carriage to prevent 35 accidental disengagement therefrom.

In describing the invention in detail reference will be had to the accompanying drawings, forming a part of this application, and wherein like numerals of reference will be em- 40

ployed for designating like parts throughout both views, in which—

Figure 1 is a perspective view showing the device in use for double harness of the breast-strap type. Fig. 2 is a front elevation of the 45 neck-yoke member or piece, showing the securing - straps in perspective and partly broken away.

To put my invention into practice, I provide a yoke member or piece 1, made of pliable material, such as leather. In order to 50 give the required strength and rigidity, this piece or member is preferably composed of a plurality of layers which are stitched or otherwise secured together. This member or yoke-piece is substantially triangular in shape, the 55 depending lobe 2 thereof having an opening 3 to receive the tip or end of the carriage or other pole. The upper two lobes 4 of the member or piece 1 are each provided with an opening through which are passed the securing-straps 5 for attachment to the harness. A strap 6 is attached to the rear face of the neck-yoke member or piece 1 for attachment to a buckle carried by the pole of the vehicle, or the strap may be attached to the pole 65 and the buckle to the member or piece 1. The employment of a member or yoke-piece of this form gives a neat appearance, and the member or piece 1 being flexible will give to the strains brought against same, whereby 70 these strains will not be delivered at a certain point on the animal's shoulders or neck—a serious objection to the neck-yoke of pole form now generally employed.

In the practice of the invention it will be 75 evident that various slight changes may be made without departing from the spirit of my invention.

Having fully described my invention, what I claim as new, and desire to secure by Letters 80 Patent, is—

A neck-yoke of approximately rectangular contour having its corners provided with lobes, said lobes being formed with openings, said neck-yoke being formed of a plurality 85 of flexible layers secured together.

In testimony whereof I affix my signature in the presence of two witnesses.

RUFUS JONES.
